No. 36,907.

Patented May 3, 1904.

UNITED STATES PATENT OFFICE.

CHARLES WHEELANS, OF TRENTON, NEW JERSEY, ASSIGNOR TO MONUMENT POTTERY COMPANY, OF TRENTON, NEW JERSEY, A CORPORATION OF NEW JERSEY.

DESIGN FOR A LAVATORY.

SPECIFICATION forming part of Design No. 36,907, dated May 3, 1904.

Application filed March 17, 1904. Serial No. 198,684. Term of patent 3½ years.

To all whom it may concern:

Be it known that I, CHARLES WHEELANS, a citizen of the United States, residing at Trenton, in the county of Mercer and State of New Jersey, have invented a new, original, and ornamental Design for a Lavatory, of which the following is a specification, reference being had to the accompanying drawings, forming a part thereof.

10 Figure 1 is a front elevation of a lavatory

embodying my design, and Fig. 2 is a top view thereof.

What I claim as new, and desire to secure by Letters Patent, is—

The ornamental design for a lavatory herein shown.

CHARLES WHEELANS.
